UNITED STATES PATENT OFFICE.

FERDINAND L. SCHMIDT, OF NEW YORK, N. Y., ASSIGNOR TO UNITED STATES ENVELOPE COMPANY, OF SPRINGFIELD, MASSACHUSETTS, A CORPORATION OF MAINE.

ENVELOP-MACHINE.

1,191,348.

Specification of Letters Patent. Patented July 18, 1916.

Application filed February 4, 1909. Serial No. 475,985.

To all whom it may concern:

Be it known that I, FERDINAND L. SCHMIDT, a citizen of the United States, residing in the borough of Manhattan, in the city, county, and State of New York, have invented certain new and useful Improvements in Envelop-Machines, of which the following is a specification.

My invention relates to an improvement in machines for making what is known as open window or transparent envelopes, that is envelopes having an opening in the portion of the envelop occupied by the address, this opening being covered by a transparent sheet of paper so that the inclosure in the envelop will disclose the address suitably written upon it through this transparent covering.

The object of my present invention is to provide an envelop machine with means for punching out the opening in the envelop blank which is to be covered by the transparent paper. Heretofore this opening has been punched out on a die press, which has been an expensive operation, but by my invention the additional expense of punching out the opening in the envelop blank to be covered by the transparent strip of paper is eliminated and the expense of making transparent envelopes reduced.

My present invention is applicable to any known type of envelop machine provided with gumming and folding mechanisms and reciprocating means for transferring the envelop blank from the gumming mechanism to the folding mechanism, preferably such as is shown in the patent to A. A. Rheutan No. 401,462, April 16, 1889. I also propose to employ means for covering the opening formed in the envelop blank by a patch of transparent paper by any suitable mechanism, preferably by such as is shown in the patent to Joseph Froehlich, No. 1,108,734, August 25, 1914.

Referring to the accompanying drawings wherein I have illustrated a preferred embodiment of my invention sufficiently to explain the principles and mode of operation thereof, and applied to an envelop machine, 50 acting in coöperation with a mechanism for applying a transparent strip of paper to the opening in the blank made by means of my invention, Figure 1 is a plan view of the machine. Fig. 2 is a front elevation of the punching mechanism. Fig. 3 is a side eleva-

tion of the machine. Figs. 4, 5 and 6 are enlarged views of envelop blanks shown in different stages of operation.

I have shown in my drawings only such parts of the envelop machine as are directly concerned in connection with my present invention.

The mechanism for gumming, folding and conveying the envelop from the gumming to the folding mechanisms with a period of dwell and also the means for applying a transparent strip to the envelop blank prior to the folding of the flaps of the envelop, form no part of my present invention. These parts of an envelop machine and the mechanism for operating them will be well understood by those conversant with this class of machines.

In detail 1 and 2 represent the frames of my machine upon whose upper sides a table 3 is mounted.

4 is a picker arch of ordinary construction, 5 is a plunger arch of ordinary construction. The patch of transparent paper to be applied to the outlook opening in an envelop blank is cut from a roll of paper 7 by mechanism supported in frames 6 and is attached by swinging conveyer arms 8 upon the envelop blank held under the plunger plate 22. This cutting and attaching mechanism is shown and described in an application of Joseph Froehlich, Serial No. 473,621, filed January 22, 1909, to which application reference may be made for a more detailed description. This cutting and attaching mechanism is driven by means of a sprocket chain 12 from the cam shaft 9.

26 is a shaft having on its left hand end a gear 10 and also the eccentrics 23. Gear 10 is in proper mesh with gear 11 situated on cam shaft 9.

13 is a driving pulley situated on one end of the cam shaft 9.

The eccentrics 23 are connected by means of the connecting rods 21 to a cross arm 27 which has a punch 20 secured to its underside.

30 is a stationary die with an opening suitable for receiving the punch 20 and also answers by means of the grooves 30^a as a guide to the conveyer bars 24 which are for the purpose of conveying the envelop blanks from station A to station B and also from station B to station C. These conveyer bars 24 are reciprocated back and forth by a

mechanism similar to that used in the ordinary reciprocating envelop machines and particularly described in the patent to Rheutan above referred to.

18 is a stripper plate secured to the die 30 with spacing blocks 31 suitably placed so as to leave an opening 28 between its under side and the top of the die 30 for the purpose of permitting the envelop blank to pass between them.

The operation of my machine is as follows: A stack of envelop blanks are placed underneath the picker arch 4 and pickers 29 on an elevating platform (not shown). 15 After gum has been applied to the under side of pickers 29 said pickers descend and apply the gum on the uppermost blank 14 of the stack as indicated by 15 in Fig. 4. The envelop blank is now in the position indicated as station A of the machine (see Fig. 1). The pickers 29 are now raised back to their normal position as indicated in Fig. 3. In the meantime the conveyer bars 24 have passed underneath them and the 20 blank 14. The blank 14 is now stripped off the pickers 29 by a suitable plate (not shown) and deposited on the upper sides of the conveyer bars 24. The blank 14 is now transported from station A to station B. 25 The punch 20 being operated upon by the cross arm 27 connecting rods 21 and eccentrics 23 descends through a suitable opening in the stripper plate 18 and somewhat below the upper side of the die 30, thus punching 30 the opening 16 through the envelop blank 14. The cross arm 27 and the punch 20 now return to their normal position as indicated in Fig. 2. The envelop blank 14 is now transported by the conveyer bars 24 35 from station B to station C.

During the punching operation just mentioned a strip of transparent paper is sev-

ered from the roll 7 and conveyer by the conveyer arms 8 to the underside of the plunger 22 which is now ready to descend on the envelop blank 14 and deposit the severed strip of transparent paper 17 on said blank so as to cover the opening punched out. The envelop blank 14 is now folded, dried and counted in the usual manner.

What I claim as my invention and desire to secure by Letters Patent is:

1. The combination with an envelop machine of the kind specified, comprising instrumentalities for gumming and folding an envelop blank and transferring the blank from the gumming mechanism to the folding mechanism, of means for forming an opening in the envelop blank between the gumming and the folding mechanisms.

2. The combination with an envelop machine of the kind specified, comprising instrumentalities for gumming and folding an envelop blank and transferring the blank from the gumming mechanism to the folding mechanism with a period of dwell, of means for forming an opening in the envelop blank during its period of dwell.

3. The combination with an envelop machine of the kind specified, comprising instrumentalities for gumming and folding an envelop blank and transferring the blank from the gumming to the folding mechanism, of means for forming an opening in the envelop blank between the gumming mechanism and the folding mechanism, consisting of a die, a stripper plate and a reciprocating punch, and means for reciprocating said punch.

FERDINAND L. SCHMIDT.
